UNITED STATES PATENT OFFICE.

WILLIAM J. IRWIN, OF SPRINGFIELD, OHIO.

DESIGN FOR A BRACKET FOR GRATES.

SPECIFICATION forming part of Design No. 13,666, dated February 27, 1883.

Application filed November 21, 1882. Term of patent 14 years.

To all whom it may concern:

Be it known that I, WILLIAM J. IRWIN, of Springfield, county of Clarke, State of Ohio, have invented and produced a new and original Design for Brackets for Grates, of which the following is a specification, reference being had to the accompanying drawings, forming a part thereof.

In the annexed drawings, which illustrate a bracket for fire-places constructed in accordance with my design, Figure 1 is a top or plan view; Fig. 2, a cross-section taken on the line *a b*; Fig. 3, a cross-section taken on the line *c d*.

The body of this bracket consists of two concentric rings, *e* and *e'*, with connections between the two rings, and a many-pointed star, *h*, arranged within the inner ring and connected at the terminals of its points with the said inner ring. The fancifully-designed connections between the two rings are somewhat in the nature of scroll-work, so as to leave numerous unoccupied spaces, *l*, between the two rings, and these said connections are preferably composed of ornamentally-formed letters constituting some desired name. The handle *i*, which radiates from the outer ring, consists of a narrow oblong plate ornamented by substantially an imitation of scroll-work, which

latter can be in the shape of letters. This ornamentation extends the length of the handle, and is inclosed by a border formed by the edge of the handle. At the side of the body of the bracket opposite to that from which the handle radiates are arranged the upwardly-curved hooks *f* and the downwardly-projecting lugs *g*. These hooks or curved portions extend outwardly from the outer ring, while the straight lugs or projections *g*, which depend from the said ring, are a little back of the plane occupied by the hooks.

Having thus described my design, what I claim is—

A design for a fire-place bracket, consisting of a body composed of two concentric rings connected together by ornamental connections, and having an ornamental figure within the inner ring, a handle radiating from said body and provided with ornamental open-work, the curved hooks, and pendent projections on the outer ring, opposite the handle, substantially as described.

In testimony whereof I have hereunto set my hand this 16th day of November, 1882.

WILLIAM J. IRWIN.
